UNITED STATES PATENT OFFICE

RASMUS R. HELLVIK, OF NEW YORK, AND SAMUEL PERLA, OF BROOKLYN, NEW YORK;
SAID HELLVIK ASSIGNOR TO SAID PERLA

DESIGN FOR A LAMP

Application filed April 21, 1930. Serial No. 35,340. Term of patent 3½ years.

To all whom it may concern:

Be it known that we, RASMUS R. HELLVIK and SAMUEL PERLA, citizens, respectively, of Norway and of the United States of America, and residents, respectively, of New York city, county of Bronx, State of New York, and of Brooklyn, County of Kings, State of New York, have invented a new, original, and ornamental Design for Lamps, of which the following is a specification, reference being had to the accompanying drawing, forming a part hereof.

Figure 1 is a front perspective view of the lamp; and

Figure 2 is a side elevational view of the same taken from the left of Figure 1.

The light source for the lamp is concealed by translucent material behind openings A.

We claim:

The ornamental design for a lamp substantially as shown and described.

RASMUS R. HELLVIK.
SAMUEL PERLA.
